DESIGN FOR A CLOTHESLINE TAUTENER

Richard C. Lewis, Winnetka, Ill.

Application October 23, 1944, Serial No. 115,915

Term of patent 14 years

(Cl. D49—1)

To all whom it may concern:

Be it known that I, Richard C. Lewis, a citizen of the United States of America, residing at 1336 Asbury Avenue, Winnetka, Illinois, have invented a new, original, and ornamental Design for a Clothesline Tautener, of which the following is a specification, reference being had to the accompanying drawing, forming a part thereof.

Referring now to the drawing, Fig. 1 is a perspective view of a clothline tautener embodying my new design, and Fig. 2 is a top plan view thereof.

I claim:

The ornamental design for a clothesline tautener, substantially as shown.

RICHARD C. LEWIS.
